UNITED STATES PATENT OFFICE.

FREDERICK ZIMMERER, OF MIDDLETOWN, CONNECTICUT, ASSIGNOR TO THE RUSSELL MANUFACTURING COMPANY, OF MIDDLETOWN, CONNECTICUT, A CORPORATION OF CONNECTICUT.

DESIGN FOR A TEXTILE FABRIC.

Application filed September 2, 1924. Serial No. 10,633. Term of patent 14 years.

To all whom it may concern:

Be it known that I, FREDERICK ZIMMERER, a citizen of the United States, residing at Middletown, in the county of Middlesex and State of Connecticut, have invented a new, original, and ornamental Design for Textile Fabrics, of which the following is a specification, reference being had to the accompanying drawing, forming part thereof.

This design comprises alternating stripes of a solid ribbed and of a speckled appear-

ance, the stripes of speckled material being comparatively wide and prominent in contrast to the solid ribbed stripes. These comparatively wide stripes of speckled material in contrast to the narrow solid stripes form a distinguishing feature of the design.

The figure is a plan view of a textile fabric, showing my new design.

I claim:

The ornamental design for a textile fabric as shown and described.

FREDERICK ZIMMERER.
